Primary Examiner — Sheryl Lane*Assistant Examiner* — Jennifer M Campbell(74) Attorney, Agent, or Firm — Dunlap Bennett & Ludwig PLLC; Brendan E. Squire(57) CLAIM

The ornamental design for an active sportswear cover-up, as shown and described.

DESCRIPTION

FIG. 1 is a perspective view of the active sportswear cover-up showing my new design;

FIG. 2 is a front elevation view thereof;

FIG. 3 is a left side elevation view thereof;

FIG. 4 is a rear elevation view thereof;

FIG. 5 is a bottom plan view thereof;

FIG. 6 is a left side elevation view thereof;

FIG. 7 is a top plan view thereof; and,

FIG. 8 is a perspective view thereof shown in use.

The broken lines in FIG. 8 showing the active sportswear cover-up in use illustrates environment and forms no part of the claim.

1 Claim, 4 Drawing Sheets(56)
